UNITED STATES PATENT OFFICE.

LUDWIG CLOS, OF NEW YORK, N. Y.

SAUSAGE-LINKING MACHINE.

Application filed June 3, 1924. Serial No. 717,530.

To all whom it may concern:

Be it known that I, LUDWIG CLOS, a citizen of the United States, residing at 227 East 126th Street, in the county of New York and State of New York, have invented a new and useful Sausage-Linking Machine, of which the following is a specification.

My invention relates to a machine for linking frankfurters or other sausages and has for its object to provide means for compressing the filled sausage or frankfurter casing at definite lengths and turning or twisting the sausages next to the ones that are being compressed.

Another object is to construct this machine, so that it can be easily and conveniently applied to sausage filling machines of existing type.

My invention will be clearly and fully understood by reference to the accompanying drawing in which similar characters denote corresponding parts and in which Fig. 1 is a front elevation of the machine; Fig. 2 a plan view of a detail of my device; Fig. 3 an end elevation thereof; Fig. 4 a plan view of another detail of my device; Fig. 5 a plan and Fig. 6 a front elevation of another detail thereof.

The entire machine is supported by means of two standards, of which only one is shown in the drawing and each of which consists of two legs 1 and a hub 2. These standards are formed with bearings for a rotary shaft 3, which carries a pulley 4 and a web frame-work 5. The hub 2 has attached to it an annular guide member 6, which is formed with a toothed sector 7. The annular guide is formed with radial spokes 8 and a central ring 9 mounted on and fixed to the hub 2 by screws 10 or the like. The guide 6, spokes 8 and ring 9 and the toothed sector 7 may be all formed of an integral piece or suitably attached to one another. The toothed sector 7, which is adapted to act as a gear, is somewhat offset laterally and relative to the units 11, that will be hereinafter more fully described. The frame-work 5 consists of a polygonal platform 5^a, which is suitably fixed to the shaft 3 by a hub (not shown) and is formed with a central web 5^b and reinforcing ribs 5^c. This frame-work 5 is adapted to be rotated by the shaft 3.

The units 11 are attached to the faces of the polygonal platform 5^a by bolts and nuts,

as at 36. Each unit comprises a substantially rectangular frame 14 (Figs. 5 and 6), in the sides 14^a and 14^b of which are provided bearings 15, 16 (Fig. 5) in which are rotatively borne the cylindrical journals 17^a, 17^b of two shafts 17^b of square cross-section. These shafts extend transversely of the frame 14 and parallel to one another and are adapted to fit corresponding square central bores provided in drums or cylinders 18^a, 18^b. At one end, each shaft 17^b carries a bevel gear 19. The two cylinders 18^a, 18^b mounted on the shafts 17^b are formed circumferentially with flat portions 20, 21, and one of the cylinders, as 18^b, has attached to each of its ends a member 22 serving as a squeezer. Each of these squeezers is in form of a cam disc whose cam portion comprises a part 23 protruding beyond the cylindrical face of the cylinder 18^b and a depression 24. Arranged in the range of each squeezer 22, is a holder 25, which is a rigid part of the frame 14 and consists of a rib-shaped vertically extending projection 26 and a pair of parallel horizontal bars or fingers 37. Each squeezer 22 is adapted, when rotated, to pass through the space between a corresponding pair of fingers 37, while the rib 26 is so admeasured that it will just miss coming in contact with the protruding part 23 of the squeezer 22. Revolubly supported in and along one side of the frame 14 of each unit 11, is a shaft 28, which carries two gears 29, a gear 27 and a half-wheel 34. The gear 27 is adapted to periodically come into mesh with the toothed sector 7 of the guide member 6, and when so meshing with it, make one full revolution, which it imparts to the cylinders 18^a and 18^b through the shaft 28, the gears 29 adapted to mesh with the gears 19 and the shafts 17^b. The gear 27 to mesh with the toothed sector 7, is correspondingly displaced in axial direction relative to the half-wheel 34. The half-wheel 34 of each unit 11 is adapted to slide on the guide 6 (Fig. 1) whenever the gear 27 is out of mesh with the toothed sector 7. The half-wheel 34 and gear 27 may be on the right-hand end of the shaft 28, as shown in Fig. 6, or on the opposite end, as shown in Fig. 1.

Between every unit 11 (Fig. 1) is a guide 32, which consists of a bifurcated member 33, whose forks or legs 33^a are adapted to straddle the web 5^b and which at their free ends are screw-threaded to pass through

holes in the polygonal frame 5^a and to be tightened thereto by nuts 13. At its upper end, said member is formed with a head piece 35, the upper face of which is arched 5 and provided longitudinally with a channel 31, which is adapted to be considerably wider than the thickness of the filled sausage casing and is made still wider at both ends, as at 32 (Fig. 2).

10 The operation of the machine is as follows:

The shaft 3 and consequently the platform 5^a are driven from a suitable source of power through a belt (not shown) engaging the pulley 4. From a suitable place near the top of the machine, the filled sausage casings are adapted to be fed intermittently into the successive units, when reaching a certain position, from a suitable table 15 top, board, conveyor or directly from a filling machine (not shown).

As the filled sausage casing is being deposited onto a unit to extend longitudinally midway between and rest upon the pair of cylinders 18^a, 18^b, the parts of the filled sausage casing adjoining the one thus deposited on the cylinders are held in the grooves or channels 31 of the guides 12, while the ends of the part of sausage casing to be 20 treated are each located in the space between the projecting portion of the vertical rib 20 and the horizontal fingers 37 of the supports. At this period, the flattened part 25 of the cylinder 18^b is so located as to permit the passage of the sausage casing under the projecting part of the rib 26.

Immediately before the gear 27 engages the toothed sector 7, the sausage casing lies midway between and on the cylinders 18^a and 18^b with its ends resting on the fingers 37 of the holders 25 (Fig. 6). After the engagement of the gear 27 with the toothed sector 7 and during the continuation of the rotation of the frame 5, the cylinders 18^a and 18^b and also the squeezers or squeezing cams 22 will receive a rotation in clockwise direction through the medium of the bevel gears 29 and 19. The protruding portions 23 of the squeezing cams 22 will then press 30 the sausage casing against the fingers 37 into the groove 30. As a result of this squeezing operation, the meat in the filled sausage casing is pushed aside at the points of pressure forming a link. During the 35 squeezing operation, the cylinder 18^a is in such a position that its flat portion 21 is in contact with the sausage casing, so that the rotation of the cylinders will not rotate the sausage casing deposited thereon. On a 40 continuous rotation, the cam part 23 releases the ends of the link and the cylinders 18^a and 18^b begin to turn the sausage link held with its ends in the depressions 30 of the holders 25. When the gear 27 arrives 45 at the opposite end of the toothed sector

7, the cylinders 18^a and 18^b have completed the turning of the sausage link, which is now ready to pass from the unit.

Each unit 11 is adapted to form one link in the filled sausage casing, only every second sausage link being formed in this fashion. The finished string of sausage links may then be deposited on a belt conveyor that may be provided on the side opposite that at which sausages are being fed into the machine or else the string of sausage links may be taken off by some special device, that may put the sausage links on a stick ready for the smoke-house.

It is understood that any number of units 80 and supports may be used and that the number of units must equal that of the guides 12. It is also understood that the units, with proper modifications, may be used separately without the revolving 85 frame-work.

What I claim and desire to secure by Letters-Patent is:

1. In a sausage linking machine, a device 90 of the character described, comprising a pair of revolving members adapted to receive between themselves a portion of a filled sausage casing and capable at certain periods of imparting a turning movement to the latter, and means including squeezers 95 operatively connected to said members and adapted to squeeze the ends of said portion of sausage casing to form a link.

2. In a sausage linking machine, a device 100 of the character described, a pair of revoluble drums adapted to receive between themselves a portion of a filled sausage casing and capable of turning the latter around itself, and means including stationary rests and revolving squeezers operatively connected to one of said drums and adapted to squeeze the ends of said portion of sausage casing to form a link, said drums being so shaped that during the squeezing operation 105 the sausage casing will not be turned.

3. In a sausage linking machine, a pair 110 of revoluble drums adapted to receive between themselves a portion of a filled sausage casing and capable at certain periods of turning the latter around itself, stationary rests at the ends of one of said drums and revoluble squeezers at the ends of and operated by the other drum adapted to squeeze the ends of said portion of sausage casing to form a link, said drums having flattened parts so arranged relative to said squeezers that said link will not be turned around itself during the squeezing operation, and means for guiding the sausage casing onto the drums.

4. In a sausage linking machine, a pair 115 of parallel drums capable of being revolved in the same direction and having flattened portions on their circumferences, stationary supports at the ends of one of said cylin- 120

ders and cam members at the ends of the other cylinder, said cam members being adapted in cooperation with said stationary supports to squeeze the ends of a part of a filled sausage casing deposited midway between and resting on said cylinders, the flat portions of said cylinders being adapted to hold the part of the sausage casing treated from turning during the squeezing operation and means for imparting rotation to said cylinders and squeezing cams.

5. In a sausage linking machine, the combination of a circular system or series of revolving uniform units and a sausage guide between each two adjoining units, each unit being adapted in a certain position to receive a predetermined length of a filled casing to form a link and said guides being adapted to hold the adjoining parts of the 10 sausage casing in position, while a link is being formed, each unit comprising means for squeezing the ends of the sausage deposited in said unit and means for turning said link around itself after the squeezing 15 operation.

6. In a sausage linking machine, the combination of a circular series of revolving uniform units and a sausage guide between each two adjoining units, each unit comprising a rigid frame, a pair of drums revolvably mounted therein and adapted to receive between themselves a piece of filled sausage casing to form a link, said drums being capable of turning said piece of sausage 20 casing upon itself, means at the ends of one of said drums for squeezing the ends of the piece of sausage casing held in said unit, and means for periodically operating said 25 cylinders and squeezers.

7. In a sausage linking machine, the combination of a circular series of revolving uniform units, each comprising a rigid frame, two drums therein adapted to be periodically rotated in the same direction and to receive a predetermined length of sausage 30 casing to form a link, stationary members at the ends of one of said drums and means at the ends of the other drum

and revolving with the latter, said revolving means being adapted in cooperation 50 with said members to squeeze the ends of a piece of sausage casing deposited in said unit and means for periodically revolving said drums, so as to turn the link of sausage casing around itself, after the squeezing 55 operation.

8. In a sausage linking machine, the combination of a circular series of revolving uniform units, each comprising a rigid frame, two drums therein adapted to be 60 periodically rotated in the same direction and to receive a predetermined length of sausage casing to form a link, stationary members at the ends of one of said drums, each comprising a stationary vertically 65 slanting member formed with a groove at its base and a pair of horizontal fingers projecting from said base, and cam members at the ends of the other drum adapted, when revolved, to pass by said vertically 70 slanting member and through the space between the pair of fingers, so as to squeeze the ends of the piece of sausage casing deposited in said unit into said groove and means for periodically revolving said 75 drums, so as to turn said sausage link around itself after the squeezing operation.

9. In a sausage linking machine, the combination of a stationary circular guide having a toothed sector, a circular series of 80 uniform units rotatively guided thereon and carrying a gear adapted to periodically mesh with said toothed sector, each unit comprising a rigid frame and a pair of drums therein adapted to be rotated by said 85 gear in the same direction and to receive a part of the filled sausage casing, squeezing means comprising stationary members at the ends of one of said drums and rotary members at the ends of the other drum, cooperating with said stationary members to squeeze the ends of said sausage to form a link, and means for periodically revolving said drums to turn said link around itself 90 after the squeezing operation.

LUDWIG CLOS.
